DESIGN FOR A PINWHEEL TOY

Irwin E. Cohn, New York, N. Y.

Application February 21, 1940, Serial No. 90,407

Term of patent 3½ years

To all whom it may concern:

Be it known that I, Irwin E. Cohn, a citizen of the United States, residing in New York, county and State of New York, have invented a new, original, and ornamental Design for a Pinwheel Toy, of which the following is a specification, reference being had to the accompanying drawing, forming part thereof:

Figure 2 is a side elevation of the same a portion of the handle being broken away for convenience in illustration.

I claim:

The ornamental design for a pinwheel toy, as shown.

IRWIN E. COHN.
